DART CONSTRUCTION

Otto M. Swartz, Chicago, Ill.

Application July 24, 1956, Serial No. 599,789

6 Claims. (Cl. 273—106.5)

This invention relates to the construction of darts designed for use in playing a game wherein a dart is directed at a target, the dart having a suction cup forming a part thereof which, when directed against a target will cause the dart to adhere to the target against accidental displacement.

An important object of the invention is to provide a dart which will not only have exceptional adhesive qualities, but one wherein the vacuum between the suction cup and target may be readily dissipated by bending the body of the dart above the suction cup laterally, thereby permitting the quick release of the dart from the target, without damage to the suction cup or dart proper.

Still another object of the invention is to provide a dart construction which will produce a more rugged and perfect assembly by the locking in of all integral parts of the dart.

Other and further objects and advantages of the invention will be hereinafter described and the novel features thereof defined in the appended claims.

Referring to the drawing:

Fig. 1 is a perspective view of a dart constructed in accordance with the invention.

Fig. 2 is an enlarged vertical sectional view through the body portion of the dart.

Fig. 3 is a perspective view of the core of the dart around which the dart is built.

Referring to the drawing in detail, the dart comprises a core around which the body of the dart is formed, the core comprising a suction cup 5 formed with upstanding ribs 6 radiating from the axis thereof, the upper surfaces of the ribs 6 being inclined downwardly towards the axis of the suction cup, as better shown by Fig. 3 of the drawing.

Formed integral with the suction cup 5, is a stem 7 which is substantially long, and provided at its upper end with a head 8.

The reference character 9 indicates the body of the dart, which is constructed preferably of sponge rubber.

The body 9 is in the form of a ball with a bore extending therethrough, which bore accommodates the stem 7, as shown by Fig. 2 of the drawing. The lower portion of the bore or body 9 rest directly on the upper edges of the ribs 6, while the upper portion of the body 9 is flattened to receive the flat inner surface of the head 8. Thus it will be seen that due to this construction the body 9 is firmly held between the ribs 6 and head 8, securely locking the body to the core of the dart.

The head 8 is formed with openings 10 that have their walls inclined towards the stem 7, the openings 10 being arranged equal distances apart providing supports for the quill ends 11 of the feathers 12 so that when the quills 11 are forced into the openings 10, the ends of the quills will contact the surface of the stem 7 causing the quill ends of the feathers to bend slightly as shown by Fig. 2, the rubber of which the body and head are formed being such that the quills of the feathers will be firmly gripped and held in position by frictional contact.

From the foregoing it will be seen that due to the construction shown and described, I have provided a dart which is exceptionally rugged to withstand the severe strain to which it may be subjected, and at the same time provide a perfect assembly by the locking in of all the integral parts of the dart, without the necessity of the use of adhesive material.

It will further be seen that because of this specific construction as set forth, the dart will be readily released

2

from the target by merely directing pressure laterally at the upper portion of the body 9 to cause the body 9 to move laterally against the ribs, relieving the point of connection between body 9 and suction cup 5 of strain incident to the twisting of the body 9 with respect to the suction cup 5. By this action the vacuum between the cup and target will be dissipated since such lateral movement of the body will permit a portion of the cup to become disconnected from the target, allowing air to enter the cup.

While the specific details of one embodiment of this invention have been herein shown and described, the invention is not confined thereto as changes and alterations may be made without departing from the spirit and scope thereof as defined in the appended claims.

What is claimed is:

1. In a dart, a core comprising a stem, a head formed integral with one end of said stem, a suction cup formed integral with the other end of said stem, a sponge rubber body in the form of a ball disposed between said head and suction cup in contact therewith, and feathers extending from said body at the opposite side of the body from said cup.

2. In a dart, a core comprising a stem having a suction cup formed at one end thereof, spaced radiating ribs extending from one surface of said suction cup, a rubber ball-like body secured around said stem resting on said ribs, a head formed on one end of said stem contacting with said body, securing the body to said stem and feathers secured to said body effecting direct line movement of said dart when directed towards a target.

3. In a dart, a core comprising a stem, a head formed integral at one end of said stem, a suction cup formed at the other end of said stem, a ball-like body constructed of sponge rubber material held between said head and suction cup in contact therewith, and feathers extending from the body at a point opposite to said suction cup.

4. In a dart, a core comprising a stem, a head formed integral at one end of said stem, a suction cup formed integral with the other end of said stem, a body in the form of a sponge rubber ball held between said head and suction cup, said stem being embedded within said body, and feathers extending from said body at a point opposite to said suction cup.

5. In a dart, a core comprising a stem, said stem having a head formed at one end thereof, a suction cup formed at the other end of said stem, a body constructed of sponge rubber formed around said stem between said head and suction cup, ribs extending from said suction cup on which said body rests, providing spaces between said ribs, and feathers secured to said head.

6. In a dart, a core comprising a stem, a suction cup formed integral with the stem at one end thereof, spaced radiating ribs extending from one surface of said suction cup, the upper edges of said ribs being beveled towards the axis of said suction cup, a rubber ball-like body secured around said stem resting on said ribs between said cup and said head, securing said body to said core, said head having openings formed therein, the walls of said openings being inclined towards said stem, and feathers having quills extended into said openings securing said feathers to said dart.
